(57) **CLAIM**

The ornamental design for a faucet, as shown and described.

DESCRIPTION

FIG. 1 shows a top perspective view of the faucet.

FIG. 2 shows a front elevation view thereof.

FIG. 3 shows a left-side elevation view thereof.

FIG. 4 shows a back elevation view thereof.

FIG. 5 shows a right-side elevation view thereof.

FIG. 6 shows a top plan view thereof.

FIG. 7 shows a bottom plan view thereof.

FIG. 8 shows a top perspective view thereof with a circle indicating a detailed portion shown in FIG. 9; and,

FIG. 9 is a detail of the surface texture of a portion of the faucet spout within the circle labeled "FIG. 9" in FIG. 8. The broken lines shown in the figures depict portions of the faucet that form no part of the claimed design.
